Primary Examiner — T Chase Nelson(74) Attorney, Agent, or Firm — Banner & Witcoff, Ltd.(57) CLAIM

The ornamental design for a shoe, as shown and described.

DESCRIPTION

FIG. 1 is a bottom front perspective view of a shoe showing my new design;

FIG. 2 is a bottom view thereof; and,

FIG. 3 is a bottom rear perspective view thereof.

The broken line immediately adjacent to the rear of the shaded area defines the bound of the claimed design and forms no part thereof. The broken line showing of the twenty-six circular shaped areas on the top of the tread elements form no part of the claimed design. The broken line showing of the twelve unshaded cross shaped areas form no part of the claimed design. The broken lines depicting the remainder of the shoe form no part of the claimed design.
